(57) **CLAIM**

The ornamental design for a luminaire, as shown and described.

DESCRIPTION

FIG. 1 is a top perspective view of the luminaire of the present invention;

FIG. 2 is a top view of the luminaire of FIG. 1;

FIG. 3 is a bottom view of the luminaire of FIG. 1;

FIG. 4 is a left side elevation view of the luminaire of FIG. 1, a right side elevation view thereof being a mirror image of the left side elevation view;

FIG. 5 is a front view of the luminaire of FIG. 1; and,

FIG. 6 is a rear view of the luminaire of FIG. 1.

The broken lines showing environmental structure are for illustrative purposes only and form no part of the claimed design.
